TELEPHONE SYSTEM HAVING TWO-PARTY LINES

Harald Valdemar Alexandersson and Otto Georg Reinhold Siewert, Stockholm, Sweden, assignors to Telefonaktiebolaget L. M. Ericsson, Stockholm, Sweden, a company of Sweden

Application March 3, 1938, Serial No. 193,758
In Sweden April 23, 1936

1 Claim. (Cl. 179—32)

The present invention relates to telephone systems having two-party lines, and relates more particularly to telephone systems of this kind provided with a central battery. In such systems it has been difficult to find a simple arrangement of the party lines which, while permitting of the setting up of connections between the two subscribers belonging to the same party line, insures secrecy of the calls. This problem has been solved through the present invention, however, which comprises the provision, for each one of the two subscriber's sets connected to a party line, of a relay which is connected in series with the set and in parallel with a half-wave rectifier in such a manner that on talking connections between the two sets the relay will remain unactuated whereas on a call between one of the subscribers and a subscriber outside the party line the relay will disconnect the other one of the subscriber's sets connected to the party line.

The invention will now be described more in detail having reference to the drawing attached to this specification and forming part thereof, which drawing shows an example of a two-party line connected to a manual telephone exchange.

Referring to the drawing, A and B are the two subscriber's sets which are connected over a party line PL to a telephone exchange. The subscriber's sets are fed with current from a central battery in the exchange. Each subscriber's set is equipped in ordinary manner with a microtelephone M₁ or M₂, a telephone receiver P₁ or P₂, a speaking transformer I_{C1} or I_{C2} and a bell R_{K1} or R_{K2}. To each subscriber's set is allotted a relay R_A or R_B, which is connected in parallel with a rectifier 15 or 16 in such a manner that the relay will operate only for a certain current direction. Provided in the telephone exchange are, among others, two relays R₁ and R₂, a jack J, and three push buttons TA, TB and TAB.

Upon a call from one of the subscribers, for example the subscriber A, the following switching operations will take place. When the subscriber, by lifting off his micro-telephone, actuates the switch hook K_{L1}, the contact 11 will be closed, a calling circuit 12 being then completed over the party line PL, through the relays R_A and R₁. The current in the circuit 12 has such a direction that the rectifier 15, which is connected in parallel with the relay R_A, does not pass any current. Consequently, the whole current will pass through the relay R_A which operates and disconnects at its contact 13, 14 the subscriber's set B from the party line PL. On operation of the

relay R₁ provided in the exchange the lamp L is lighted due to the closing of the relay contact 17. The operator now inserts a plug in the jack J, causing the relay R₂ to be energized over a contact 18. On operation the relay R₂ interrupts at 5 its contact 19 the current through the lamp. If the call is intended for another subscriber than the subscriber B, the connection can now be completed in ordinary manner. If, on the other hand, the subscriber A desires to be connected to 10 the subscriber B belonging to the same party line, the operator must first press the push-button TB in order to be able to effect the setting up of the connection. The pressing of the push-button TB causes the circuit 12 to be interrupted and the 15 relay R_A to drop its armature, rendering it possible to send a ringing signal over a contact 21 closed by the push-button TB, and one branch of the party-line, and the switch hook K_{L2} to the earthed bell R_{K2} of the subscriber B. During the ringing period the relay R_B operates and disconnects the subscriber's set A. On release of the push-button TB by the operator the ringing signal will cease. The operator thereafter pushes the button TAB. The current feed relay R₁ 20 of the exchange will then be connected to the party-line TL, so that the direction of the current in the line TL will now be opposite to the direction of the current upon a call, resulting in that neither the relay R_A nor the relay R_B can attract its armature, in that for the direction of the current now set up both of said relays will be shunted by the appertaining rectifiers 15 and 16. When the subscriber B has answered the call both 25 of the subscribers A and B will be in talking connection with each other over condensers C₃, C₄ connected in parallel with the relays R_A and R_B. During the conversation between said subscribers the operator can remove the plug, the relay R₂ being held energized over a contact 22 provided 30 on the push-button TAB. As soon as the conversation has been finished and the microtelephones replaced on the switch-hooks the relay R₁ will drop its armature, the lamp L being then 35 ignited because of current supplied over contacts 23 of the relay R₂. When thereafter the operator pulls out the button TAB, the relay R₂ will be deenergized and the lamp goes out.

A call to one of the subscribers A or B coming from the telephone exchange is put through under co-operation of the operator. After a plug has been inserted in the jack J a ringing signal can be transmitted to the wanted subscriber A, B by depressing the proper one of the ringing buttons TA and TB. As soon as the called sub- 40 45 50 55

scriber answers, the corresponding relay RA or RB respectively will attract its armature and disconnect the other subscriber. When after completed conversation the microtelephone of the 5 party-line subscriber is put back on the switchhook the relay RI is de-energized and the lamp L is lit, whereupon the operator releases the connection.

In the embodiment illustrated in the drawing 10 the two-party line arranged according to the invention is connected to a manual telephone exchange. However, the invention can be realized also in connection with automatic telephone exchanges. The reversal of the direction of the 15 current in the party line TL which is effected in the illustrated embodiment by the operator by means of the button TAB can be effected in an automatic system by means of a relay which is actuated from a device operated by the numerical impulses, for example a selector, a register or 20

a follow-up device when the calling subscriber A has dialled the number of the subscriber B connected to the same line.

We claim:

In a telephone system having two party lines 5 connected to a central battery, a relay individual to each subscriber branch line and connected in series with said branch line, each of said relays adapted when energized to disconnect the other subscriber branch line, a half-wave rectifier connected in parallel with each of said relays and so directed that the current normally sent from the central battery during a conversation between one of the two party line subscribers and a subscriber outside the party line actuates said 10 relay, and means for reversing the direction of the current during a connection between the two subscribers of the same party line.

HARALD VALDEMAR ALEXANDERSSON.
